Primary Examiner — Jennifer Rivard(74) *Attorney, Agent, or Firm* — Perkins Coie LLP(57) **CLAIM**

The ornamental design for a hair iron brush, as shown and described.

DESCRIPTION

FIG. 1 is a top plan view of an embodiment of a hair iron brush showing my new design.

FIG. 2 is a bottom view thereof.

FIG. 3 is a side view thereof illustrating the hair iron brush in a closed position, the opposite side being a mirror image thereof.

FIG. 4 is a side view thereof illustrating the hair iron brush in an open position.

FIG. 5 is a front view of FIG. 1; and,

FIG. 6 is a back view of FIG. 1.

The broken lines illustrate portions of the hair iron brush and form no part of the claimed design.
